UNITED STATES PATENT OFFICE.

ERNEST J. TURNER, OF PITTSBURGH, PENNSYLVANIA, ASSIGNOR OF ONE-THIRD TO BLOOMFIELD H. HOWARD, OF ASPINWALL, PENNSYLVANIA.

FEEDER FOR INGOT-MOLDS.

1,022,343.

Specification of Letters Patent.

Patented Apr. 2, 1912.

Application filed January 24, 1912. Serial No. 673,098.

To all whom it may concern:

Be it known that I, ERNEST J. TURNER, a citizen of the United States, and a resident of Pittsburgh, in the county of Allegheny 5 and State of Pennsylvania, have invented certain new and useful Improvements in Feeders for Ingot-Molds, of which the following is a specification.

My invention relates to the manufacture 10 of steel and iron ingots and has for its object to prevent the formation of what is known as "piping" and "seaming" in casting ingots.

Many devices have been devised for this 15 purpose, but all of them have either been inadequate or have been so complicated and expensive as to preclude their coming into general use. The particular kind of devices used for this purpose and which more nearly 20 resemble my feeder, are only adapted for casting small ingots, and even for such ingots, they have been found impracticable. This is due to the fact that they have contracted portions or throats, which so retard 25 the flow of the molten metal that it becomes cooled, or what is known in the trade "freezes" in the feeder, so that it will either not flow through the feeder, or if it does, it flows very slowly and this together 30 with the fact that it enters the mold only at the center, the metal at the sides of the mold oxidizes, and consequently when the inflowing metal does spread out toward the sides, it flows over this oxidized surface, and the 35 result is that lateral "pipes," or "seams" or both are formed in the ingot.

I have found by experiment that in order 40 to prevent "piping" and "seaming" in casting ingots it is necessary that the molten metal be poured into the mold in a highly heated state and as rapidly as possible. With this in view I have devised a feeder made of refractory material so that it can be heated and I provide it with a large 45 and unrestricted opening or passage through which the molten metal is poured into the mold, so that the metal is prevented from being chilled and flowing rapidly through the feeder, it distributes itself evenly 50 throughout the entire surface of the mold, thus reducing "piping" and "seaming" to a minimum.

A practical embodiment of the invention 55 is represented in the accompanying drawings forming a part of this specification, in

which similar characters of reference indicate corresponding parts in all the views.

Figure 1 is a sectional view of the improvement showing it applied to a mold with an ingot therein, the ingot and mold 60 being broken away and in section; Fig. 2 is a perspective view of the feeder on an enlarged scale, and Figs. 3 and 4 are sectional views of modifications.

Referring to Figs. 1 and 2 of the drawing, 65 A is a mold of any approved construction, a an ingot therein, and B the feeder. The feeder B is formed of fire clay or other refractory material and consists of the body b, and neck b' integral with the body and 70 of a size to fit snugly in the mold. The body b is made quite large so as to retain the heat and it may be square, round or any other suitable shape.

At the junction of the neck with the body 75 a shoulder b² is formed and through the body and neck a passage or opening b³ extends. The portion of the passage or opening b³ in the body of the feeder is of uniform diameter, while the portion in the 80 neck is of gradually increasing diameter from its upper to its lower end. The varying diameter of the opening or passage in the neck is formed by beveling the inner surface of the wall of the neck downwardly 85 and outwardly. This beveling of the wall of the neck not only enlarges the passage or opening of the neck, but it reduces the thickness of the wall of the neck at its lower end, so that the metal can readily flow to 90 the sides of the mold clear up to the lower end of the said neck.

The wall of the neck of the feeder is made as thin as possible consistent with 95 strength, so that the passage or opening through the feeder can be made nearly of as great a diameter as the diameter of the mold, so that a large quantity of molten metal can be poured into the feeder, and as the passage or opening thereof is unrestricted it passes rapidly through the same into the mold.

In Fig. 3 I have shown the opening or 105 passage b⁴ of the feeder B' of uniform diameter throughout. In other respects the feeder is similar to that shown in Figs. 1 and 2. While this form gives good results, yet I prefer to form the opening or passage of the neck of the feeder of gradually increasing diameter as shown in Figs. 1 and 2. 110

In Fig. 4 the feeder B² is shown with two necks b⁵ and b⁶ of unequal length so that it can be reversed for casting ingots of different lengths. The body b¹ is of uniform diameter throughout instead of tapering as shown in the other figures.

In operation the feeder being heated it is placed upon the mold with its shoulder resting upon the end of the mold and its neck extending into the same. The molten metal is now poured as usual in forming large ingots, from a ladle into the feeder, and owing to the feeder being heated and having a large and unrestricted passage or opening, the molten metal is kept heated and flowing rapidly through the feeder into the mold, distributes itself evenly throughout the whole area of the mold so that a homogeneous ingot is formed.

It will thus be seen that I have produced a very simple, cheap and efficient feeder and one especially adapted for casting large ingots.

Having thus described my invention, what I claim and desire to secure by Letters Patent is:

1. As a new article of manufacture a

feeder for ingot molds, formed of refractory material and comprising a body having an unrestricted passage and provided at one end with a neck adapted to extend into a mold and having a comparatively thin wall and a shoulder at the junction of the neck with the body to rest upon the end of the mold, the passage of the body being of uniform diameter and the passage of the neck being of gradually increasing diameter from its upper to its lower end.

2. As a new article of manufacture a feeder for ingot molds formed of refractory material and comprising a body having an unrestricted passage and provided at one end with a neck to extend into a mold and with a shoulder at the junction of the neck with the body to rest upon the end of the mold, the wall of the neck being comparatively thin, whereby the passage through the feeder will be of a diameter nearly equal to that of the mold upon which the feeder is used.

ERNEST J. TURNER.
